Filed Jan. 20, 1960, Ser. No. 59,119

Term of patent 14 years

(Cl. D9—2)

Figure 1 is a front elevational view of an ultrasonic cleaning unit for small parts showing my new design.

Figure 2 is a side elevational view taken from the right of Figure 1.

Figure 3 is a top plan view thereof.

Figure 4 is a side elevational view taken from the left of Figure 1.

Figure 5 is a rear elevational view thereof.

Figure 6 is a bottom plan view thereof.

The dominant features of my design reside in the full line portions of the drawing.

I claim:

The ornamental design for an ultrasonic cleaning unit for small parts, as shown and described.
